ELECTRICAL SWITCH

John E. Helminak, Washington, D.C., and Jules H. Sreb, Silver Spring, Md., assignors to the United States of America as represented by the Secretary of the Navy

Application March 12, 1946, Serial No. 653,910

6 Claims. (Cl. 200—61.46)

The present invention relates to improvements in electrical switches, more particularly to manually-operated switches of the rotary type for use in ammunition.

An object of the invention is to provide an improved rotary electrical switch.

Another object of the invention is to provide an improved manually-operated, rotary, electrical switch of extremely simple, small, light, economical and rugged construction.

A further object of the invention is to provide a manually-operated switch for use in relation to electric firing circuits in all types of military missiles (projectiles, bombs, torpedoes, rockets, mines, depth charges, etc.), which will not only withstand the shock of being fired from a gun, tube, or equivalent device and the heavy stresses attendant on high speeds of rotation and translation, but also, in which locking members will prevent the opening or closing of the switch under such shock and stresses.

An additional object of the invention is to provide a rotary electrical switch for ammunition in which the position is unmistakably indicated on the exterior of the switch.

Another object of the invention is to provide an electrical safety switch suitable for use in military missiles having electrical detonating means for arming or disarming the firing circuit.

In the accompanying drawings:

Fig. 1 is a plan view of the switch.

Fig. 2 is an exploded perspective view of the switch assembly.

Fig. 3 is a vertical cross-section on the line 3—3 of Fig. 1.

Fig. 4 is a vertical cross-section on the line 4—4 of Fig. 1.

Fig. 5 is a side view of a fuze case, partly broken away, and with a portion of the wall in longitudinal section, to show a suitable location of the switch as used in such devices.

This switch is adaptable to a wide variety of uses. It is particularly designed as a control device for the electrical operating circuit of a fuze in a high explosive projectile. For this purpose, a small compact switch is necessary; one which may with facility be installed in an accessible portion of the fuze case and provided with reliable safety means for indicating the "On" and "Off" condition of the circuit, thus giving warning of the armed or unarmed condition of the fuze. In carrying out the invention, a minimum number of parts are employed to insure a reliable and rugged construction and to impart simplicity in operation to the device.

Throughout the drawings the switch is shown in the closed position to avoid any confusion.

Basically, the switch 10 consists of a housing 11 and a rotor 12. The housing 11, which is nominally the "stationary" member of the switch, with respect to which the rotor turns, is shown here as an externally-threaded bushing made from any suitable electricity-conducting ma-

terial such as brass. It is provided with an internal annular flange 13 for supporting, guiding and retaining the rotor 12. Spring contact arms 14 are L-shaped and the legs 15 thereof are soldered or brazed into sockets on the 5 opposite sides of housing 11. The housing has slots 16 to accommodate the spring contacts, the slots being deeper at the free ends of the contacts. By making the bend in these L-shaped spring contacts 14 somewhat less than 90 degrees and deepening slots 16 at the free ends 10 of the contacts, the spring contacts bear positively against the movable tab contacts 17 to be described later, thereby assuring good contact.

The rotor 12 consists of two annular, insulating washers 18 and 19 bound together by a tubular, open-ended rivet 20 of brass or other good conducting material. Lower washer 19 is provided with a diametrical groove 21 and also with a rabbet 22 which fits against the internal flange 13 of the housing 11. The upper washer 18 is provided with a complementary, diametrical tongue 23 on its lower side which fits into the groove 21 of lower washer 19 when the rotor 12 is assembled. The tongue and groove assembly prevents any relative turning movement between the upper and lower washers by interlocking them.

25 Inasmuch as upper washer 18 bears on the upper face of internal flange 13 and lower washer 19 bears on the lower face of this flange, when fastened together by the rivet 20 the washers retain the rotor within the housing and prevent dislocation by centrifugal or other forces.

30 On its lower end the rivet 20 is fashioned with flat, tab contacts 17 which extend radially from the rivet and are fitted into shallow recesses in the under side of lower washer 19. These tab contacts 17 constitute the movable contacts of the switch, and when turned to the closed position ride on top of spring contacts 14. The electrical lead 24 is soldered or brazed to the interior of the rivet 20. The circuit through the switch 10 is as follows: current entering through the lead 24 flows through rivet 20 into the tab contacts 17, and from there into the two spring contacts 14 when the switch is closed, and thence to the housing 11 which is grounded. This grounding is accomplished by the contact of the external threads of the housing with the body into which it has been screwed.

45 The housing 11 is slotted radially at 25 and the upper washer at 26. When washer slot 26 is aligned with the housing slots 25 as shown in Fig. 1, a slot is formed which extends through the top of rivet 20 and completely across the switch. These slots have several functions. When aligned they indicate that the switch is closed or in the "On" position. Housing slots 25 also permit the insertion of the switch into a body by means of a spanner wrench; however, if washer slot 26 is aligned with slots 25, a broad-bladed screwdriver may be used instead.

50 The switch 10 is turned "On" (closed) or to the "Off" (open) position by means of a smaller screwdriver or any other suitable tool engaging washer slot 26 alone. Releasable safety detent 27 serves as a locking means for the switch by engaging peripheral notch 28 of washer 18 in the "On" and the end of washer slot 26 in the "Off" position. This detent is fashioned of spring wire and lies in a recess 29 of housing 11. The opposite end of detent 27 is anchored to the housing 11 by any suitable 60 means, such as a tangentially-directed hole or socket or soldering or brazing.

Limit stops to restrain the movement of rotor 12 to proper limits are provided by the ends of arcuate way 30 in the upper washer 18 and the stop 31 mounted on 70 the housing 11. This stop may be attached to the housing by any suitable means; as shown in Fig. 3, it consists of a piece of wire fitted into a socket in the internal

flange and soldered or brazed along the inside of the housing 11 and the notch at the top of the housing.

Fig. 5 shows the position of the switch 10 when mounted in a fuse case 32. The switch is then mounted in a tapped hole by simply screwing in the housing 11 by means of a screwdriver or spanner wrench. After the fuze mechanism is inserted in the case 32, it is only necessary to fish lead 24 through the tubular rivet 20 and solder or braze it to the interior of this rivet.

A particular application of this switch is to short out the firing circuit of the electrical detonator or primer in order to maintain the projectile in an unarmed condition when so desired for safe handling. Then in the event of any accidental leakage of current into the firing circuit, this current would be short-circuited through lead 24, rivet 20, tab contacts 17, spring contacts 14, and housing 11 to fuse case 32 instead of firing the primer.

Switch housing 11 is shown as a bushing; but this is merely one application and various other types of housings can be used as the occasion demands.

The operation of the switch, shown in Fig. 1 in the closed or "On" position, requires only the insertion of a screwdriver blade into the washer slot 26 and a counter-clockwise turn of 90 degrees. The force of turning will disengage detent 27 from the peripheral notch 28, and at the end of the turn this detent will then engage the end of washer slot 26. The righthand end of arcuate way 30 will by then have reached stop 31 and will prevent any further turning in that direction. This, of course, turns the rotor assembly of the two washers and the rivet thereby displacing the tab contacts 90 degrees, sliding them away from spring contacts 14; the movement of tab contacts 17 away from the spring contacts 14 breaks the circuit. The switch is now in the open or "Off" position which will be indicated by washer slot 26 being out of alignment with housing slots 25. To turn the switch to the "On" position, it is only necessary to reverse the above process by turning the rotor 90 degrees clockwise. The alignment of the washer slots with the housing slots indicates that the switch is closed on "On."

From the manner of mounting the switch 10 in fuze case 32 it is obvious that rotation at high speeds will not derange contacts or components of the switch in any manner; as spring contacts 14 will be retained within the notches 16, tab contacts 17 will remain anchored in the recesses in lower washer 18, and the rotor will be retained by the internal flange 13 of the housing 11 and prevented from rotating by the detent 27.

While the preferred embodiment of the invention has been described herein, the device is obviously capable of a wide variety of adaptions and applications where a rugged, economical, simple switch of the locking, rotary type is desired.

We claim:

1. In an electrical switch including a housing having a pair of spaced spring arms forming stationary contacts, the combination of a rotor and coating retaining means on the rotor and housing, a tubular open-end rivet

mounted in the rotor, and a pair of contact arms integral with the rivet for frictional engagement with said spring arms.

2. An electrical switch adapted for mounting in a projectile subjected to centrifugal forces comprising, a housing having a pair of spaced spring arms forming stationary contacts, a rotor forced of insulating material positioned in said housing, resilient retaining means releasably securing the rotor in the housing against rotation, a tubular rivet mounted in said rotor, a pair of contact arms integral with the rivet and making frictional engagement with said spring arms in one position of said rotor, and means for limiting the rotor against accidental displacement caused by the effects of centrifugal force.

3. An electrical switch for use in a projectile subjected to centrifugal forces comprising, an externally-threaded housing having a bore and flange therein, a rotor of non-conducting material rotatably mounted in said bore and having an annular groove coaxing with said flange to effectively retain said rotor in the housing against accidental displacement caused by the effects of centrifugal force, spaced spring contacts on said housing, an open-ended tubular rivet mounted in said rotor, a pair of contact arms integral with the rivet and making frictional engagement with said spring contacts in one position of said rotor, coaxing stop means on said housing and rotor for limiting the relative rotation thereof, resilient means for releasably securing the rotor in either of two possible positions within the housing, and means on the exterior of said rotor for indicating and controlling the position of the said contact arms relative to the said spring contacts.

4. An electrical switch including a housing, a resilient conducting arm mounted in the housing and constituting a relatively stationary contact, a sectional rotor rotatably mounted in the housing, means connecting the sections of the rotor to each other, said housing having a flange, said flange and means coaxing for retaining the rotor in the housing, and a contact carried by said means and movable therewith, upon rotation of the rotor, into and out of engagement with the stationary contact.

5. An electrical switch as recited in claim 4, wherein said means is constituted by a rivet.

6. An electrical switch as recited in claim 4, wherein said rotor is formed with a slot, and including a detent carried by the housing and engageable in the slot.
